VOLTAGE REGULATOR SYSTEM

Filed June 10, 1929

FIG. 2.

INVENTOR
W. P. KOECHEL
BY *M. F. Beger*
ATTORNEY

UNITED STATES PATENT OFFICE

WALTER P. KOECHEL, OF BLOOMFIELD, NEW JERSEY, ASSIGNOR TO WESTINGHOUSE LAMP COMPANY, A CORPORATION OF PENNSYLVANIA

VOLTAGE REGULATOR SYSTEM

Application filed June 10, 1929. Serial No. 369,906.

This invention relates to electrical systems and more particularly relates to electrical systems employing voltage regulator devices of the gaseous conduction type, and has for its object the provision of a means of effecting the regulation of a fluctuating source of voltage to obtain therefrom a substantially constant voltage.

Another object of this invention is to provide a voltage regulating system utilizing a plurality of glow regulator tubes, in which the electrical load of the system is equally distributed between the regulator tubes.

Another object of this invention is to provide a system for operating low voltage electrical apparatus at a substantially constant potential from a high voltage source of fluctuating potential.

Another object of this invention is to provide a voltage regulating system employing a plurality of glow regulating tubes in which the distribution of the electrical load between the tubes may be adjustably equalized.

Other objects and advantages will herein-after appear.

In accordance with the objects of my invention I have found that in a voltage regulating system employing a plurality of gaseous conduction regulator devices of a type such as is disclosed in copending application of Harvey C. Rentschler, Serial No. 158,503 filed January 3, 1927, entitled Electron discharge device, which is assigned to the same assignee as the present invention, it is essential for the successful operation of the system that means be provided for equally distributing the electrical load of the system between the respective voltage regulating devices utilized therein.

Devices of the type disclosed in the above identified copending application by Harvey C. Rentschler are comprised substantially of an enclosing glass envelope containing a cylindrical cathode of relatively large area, a centrally disposed anode of small area and a filling of an inert monatomic gas such as argon, at a pressure of about 5 to 6 m. m. of mercury. The anode consists at least in part of thorium and a getter material such as misch metal is employed on the cathode for puri-

fying the gas filling and for lowering the starting and operating potentials of the tube.

One of the characteristics of such a tube is that it has a nearly constant voltage drop across its terminals when the current flow therethrough varies over a considerable range, and this characteristic has been utilized for maintaining a constant voltage across the terminals of electrical apparatus connected in shunt relation to the regulator tube.

It is found, however, that the current carrying capacity of the device is limited by the size of the cathode and it is inexpedient from a manufacturing and commercial application standpoint to increase the size of the cathode beyond the point which provides a current carrying capacity in the tube of approximately 2.0 amperes.

In electrical systems employing such devices in which a current greater than the carrying capacity of a single tube is flowing, it is essential that a plurality of such devices be utilized in parallel to prevent overloading of a single tube.

The voltage drop of a voltage regulator tube of approximately 2 ampere current carrying capacity is designed to be approximately 100 volts.

It is found, however, that due to manufacturing variables over which there is little control, the voltage regulator tubes individually vary from 95 to 105 volts in the voltage drop across the tubes. In connecting these tubes in parallel in any given electrical system the tube having the lowest voltage drop will draw the major portion of the current and thus become overloaded. Additional voltage dissipating means must therefore be provided for individually equalizing the tube resistances so that each tube will draw substantially identical amounts of current from the circuit.

I accomplish this result by providing in series with the voltage regulator tube a potentiometer. One side of the tube is brought to a center tap of the potentiometer. One terminal of the potentiometer then is connected to the ground and the other terminal to a source of positive potential intermediate

the source of positive potential actuating the regulator tube and ground potential and preferably lower than the operating potential of the said voltage regulator tube. By varying the setting of the potentiometer center tap the voltage drop across the tube may be varied, and the current that may be drawn by the tube thus adjusted to any desired figure. By connecting a plurality of these tubes in a similar manner, in parallel from a common source of positive potential each tube may thereby be adjusted to draw any desired current from the circuit.

By applying a current of approximately constant voltage across the tubes, the individual current carrying capacities of the tubes may be regulated and equalized by means of the variable adjustment on the individual potentiometer.

Before further disclosing the nature of my invention reference should be had to the accompanying drawings wherein

Fig. 1 represents a schematic diagram of an electrical circuit embodying the features of my invention; and

Fig. 2 shows a side elevational view partly in cross section of a voltage regulator tube of the gaseous conduction type utilized in the electrical circuit in Fig. 1.

In Fig. 1 is shown a 250 watt 64 volt headlight lamp (1) of the type commonly utilized on electric locomotives, street cars and the like, connected across the line voltage C and D. The line voltage is liable to fluctuate widely such as from a minimum of 300 volts to a maximum of 900 volts. Suitable dissipating resistances 5, 6 and 7 are interposed in series with the lamp 1 across the terminals to reduce the variable line voltage to the desired lamp voltage of approximately 64 volts. It is desirable to protect the lamp from premature burnout by means of voltage regulator tubes 2, 3 and 4 of the gas discharge type having a voltage drop of approximately 100 volts, which tubes are connected in parallel with the incandescent lamp from a point (A) in the dissipating resistances 5 and 6 which gives approximately a 100 volt drop to ground potential.

Interposed between the negative terminal and the voltage regulator tubes and electrically connected in parallel are variable potentiometers 8, 9 and 10 having one terminal of each connected to the negative or ground potential and the other terminal connected back to a source of positive potential on the negative side of the lamp. A dissipating resistance 7, of approximately an equal value to the variable resistance of the potentiometers 8, 9 and 10 is interposed between the negative terminal of the circuit and the lamp. The cathode of the voltage regulator tube is connected to the center tap of the potentiometers in the manner indicated.

The glow discharge regulator tubes 2, 3 and

4 in addition to the regular anode 11, and cathode 12, have an auxiliary or starting electrode 13 which is connected to a source of higher potential (B) to facilitate the breakdown and operating characteristics of the 70 regulator tubes.

In accordance with my invention the individual voltage regulator tubes are separately adjusted by means of passing through the system a voltage of constant potential approximately the maximum voltage to which the system is to be exposed, and the individual tubes separately adjusted by means of the variable resistances 8, 9 and 10 to draw the desired amount of current from the circuit at 80 that voltage. Thereafter the circuit may be operated from any desired fluctuating source of high potential approximating this voltage and the tubes will always individually draw equal currents thereby substantially preventing any single tube from becoming over-loaded.

In the present instance as indicated on the schematic diagram the line voltage may fluctuate between 400 to 750 volts. The normal 90 voltage of the circuit is approximately 600 volts. Lamp 1 operates on 64 volts. It is necessary to have in series with the lamp 1 a dissipating voltage of approximately 536 volts.

The carrying capacity of a single voltage regulator tube is approximately 2 amperes. By connecting a plurality of these tubes in parallel a regulator circuit of any desired carrying capacity may be obtained. For the service contemplated at the present the total maximum amperage that may be present in the circuit is approximately 12 amperes. The average current is approximately 3 to 5 amperes.

There is liable to be at any moment surges of current greatly in excess of this amount of current. In the event of lamp burnout the regulator tubes must be capable of carrying constantly for prolonged periods of time approximately 12 amperes of current. I therefore prefer to connect in the parallel circuit a total of 12 voltage regulator tubes, adjusting each tube to carry a maximum of 1 ampere at normal operating voltage. This 115 provides a 100 per cent margin of safety and in the event of lamp failure the entire load of the circuit may be carried indefinitely by the tubes without injury thereto.

Having broadly and specifically outlined 120 the nature of my invention it is apparent that there are many variations and departures that may be made from the specific embodiment thereof without essentially departing from the nature thereof, and such variations and departures are anticipated which fall within the scope of the following claims:—

What is claimed is:

1. In an electrical system comprising a va- 130

- riable source of high potential, a dissipating resistance to obtain a current of lower potential, an electrical device operating at this lower potential, and a gas discharge voltage 5 regulator tube to maintain said lower potential constant, of a variable resistance electrically connected in series with said gas discharge tube from a center tap connection of said variable resistance, said resistance being connected at one end to ground potential and at the other end to a source of positive potential less than the starting potential of said gas discharge tube. 10 2. In an electrical system comprising a variable source of high potential, a dissipating resistance to obtain a current of lower potential, an electrical device operating at this lower potential and a plurality of gas discharge devices for maintaining said lower potential 15 constant, of means for regulating the individual current carrying capacities of said gas discharge devices comprising a variable resistance connected electrically in series with each of said gas discharge tubes to a mid tap connection of said variable resistance, one end of each of said resistances being grounded and the other end of each of which are connected in parallel to a source of positive potential less than the operating potential of 20 said gas discharge device. 25 3. In an electrical circuit comprising a variable source of high electrical potential, a dissipating resistance means for obtaining a current of lower potential, an electrical device operating at this lower potential and voltage regulating means to maintain said lower potential substantially constant, comprising a gas discharge voltage regulator tube, the means for regulating the current 30 consuming properties of said gas discharge tube comprising a variable resistance having a center tap member electrically connected to the cathode electrode of the gas discharge tube, one of the terminals of said resistance being connected to ground potential, the other terminal being electrically connected to a source of positive potential lower than the operating voltage of said gas discharge device. 35 4. In an electrical circuit comprising a variable source of high electrical potential, dissipating resistance means to obtain a current of lower potential, an electrical device operating at this lower potential, and voltage regulating means in parallel to said electrical device comprising a gas discharge tube for maintaining said lower potential constant, the means for regulating the current consuming properties of said gas discharge tube comprising a variable dissipating resistance potentiometer in series therewith and electrically connected thereto from a center tap connection to one of the electrodes of said gas discharge tube, one of the terminals of said 40 potentiometer being connected to the negative side of the said electrical circuit and the other terminal to a source of positive potential on the negative side of the said electrical device. 5. In an electrical circuit comprising a variable source of high electrical potential, dissipating resistance means for reducing said potential to a lower potential, an electrical device operating at this lower potential, and a plurality of gas discharge regulator tubes for maintaining a constant lower potential for said electrical device, of means for equally distributing the electrical load of the circuit among said gas discharge regulator tubes comprising a plurality of variable resistances having a center tap connection, means for electrically connecting the cathode electrode of each of said regulator tubes to one of said center tap connections, means for electrically connecting one side of each of said variable resistances in parallel to a source of positive potential less than the operating voltage of said voltage regulator tube and means for electrically connecting the other side of each of the said variable resistances in parallel to the ground potential of the variable source of high potential. 70 75 80 85 90 95 100 105 110 115 120 125 130
- In testimony whereof, I have hereunto subscribed my name this 7th day of June, 1929.
- WALTER P. KOECHEL.
